UNITED STATES PATENT OFFICE.

SHERIDAN A. WALKER, OF ELMHURST, NEW YORK, ASSIGNOR, BY MESNE ASSIGNMENTS, TO THE WALKER COMPANY, OF WILMINGTON, DELAWARE, A CORPORATION OF DELAWARE.

SHIFTABLE CAR-SEAT.

1,252,747.

Specification of Letters Patent.

Patented Jan. 8, 1918.

Application filed September 2, 1914, Serial No. 859,734. Renewed June 2, 1917. Serial No. 172,525.

To all whom it may concern:

Be it known that I, SHERIDAN A. WALKER, of Elmhurst, in the county of Queens, and in the State of New York, have invented a certain new and useful Improvement in Shiftable Car-Seats, and do hereby declare that the following is a full, clear, and exact description thereof.

My invention relates particularly to car seats designed for vehicles, but it is especially adapted for application to car seats used on railway carriages.

The object of my invention is to provide a car seat in which the back and the seat, as well as the foot rest, may be shifted from one side to the other, so that the seats may be reversed according to the direction of movement of the car and according to the wishes of the passengers.

Another object of my invention is to provide a seat of this character in which the lost motion in elevating the back in the shifting operation is reduced to a minimum so as to avoid unnecessary work in elevating the back in the shifting operation, and so as to avoid damage to the parts which may occur where the seat is elevated to a considerable degree and therefore has to fall a considerable distance in the last portion of the shifting movement.

An object of my invention is therefore to provide a shifting mechanism for car seats in which the back need be elevated only to a sufficient extent to insure that the back and the other movable portions of the car seat will be retained in their shifted positions when shifted.

Another object of my invention is to provide a car seat in which the shifting mechanism is inclosed in a casing of an advantageous character, said casing being so constructed as to effectually brace the seat, notwithstanding the light weight of the parts of the casing.

Another object of my invention is to support the arm rest of the seat in an advantageous manner so that the same will not be broken off the end of the seat nor deflected from its proper position by the application of heavy weights as, for example, when persons are sitting thereon.

While my invention is capable of embodiment in many different forms, for the pur-

pose of illustration I have shown only one form thereof in the accompanying drawings, 55 in which

Figure 1 is a vertical section of the seat made in accordance with my invention;

Fig. 2 is a vertical section showing the outer plate and inner plate at the end of the 60 car seat; and

Fig. 3 is a horizontal section through the same.

In the drawings I have shown a back 1 which is supported upon two arms 2 having 65 widened lower ends 3. Each of the arms 2 at its lower end is connected at the two sides thereof with levers 4 by means of journals 5. Each of the levers 4 has an enlarged lower end 6 at the corners of which there are provided a pair of recesses 7. The recesses 7 coöperate with pins 8 to support the back 1 in place. The pins 8 are situated between an inner plate 9 and an outer plate 10 which have holes to receive the same, said pins 8 75 having their ends headed to hold the pins in place. It will be noted that there are three of the pins 8 located at each end of the car seat, one of said three pins being located in the center of the car seat while the 80 other two pins 8 are spaced an equal distance therefrom. It will also be noted that inasmuch as the central pin 8 is designed to coöperate with both of the levers 4 at a particular end of the car seat, one of 85 these levers 4 at each end of the car seat is provided with an offset portion 8' in order not to contact with the adjacent end of the other lever 4. Each of the levers 4 has at about the center of its lower end a circular 90 boss 11 to which is riveted a rod 12. The rods 12 extend from one end of the car seat to the other so as to connect the corresponding levers 4 at the two ends of the seat together. Furthermore, each of these rods 12 95 is adapted to move, together with its corresponding boss 11, in a guiding slot 13 located in the inner plate 9 at each end of the car seat. These rods 12, by connecting the corresponding levers 4 together, give a uniform 100 shifting movement to the two ends of the car seat so that the car seat may be shifted without any twisting movement. On the inner face of the inner plate 9 I provide a pair of circular sockets 14 attached to the plate by 105 means of rivets 15 for receiving cross rods

16. These cross rods 16 support the car seat from a pedestal 17, which may be located at one end of the car seat, while yokes or straps 18 pass from the pedestals 17 around the 5 cross rods 16 to hold the same in place, the yokes 18 being held in position by bolts 19 passing through the same and through the pedestals 17. At each end of the car seat, connecting the rods 12, there is a carriage 20 having in the center thereof a pivot 21 for connecting thereto, at each end of the car seat, a foot rest lever 22. The carriage 20 at each end of the car seat has slots 20^a to receive the rods 12. The two foot rest levers 10 15 22 are connected together by a foot rest 23. The foot rest levers 22, furthermore, extend upwardly above the carriages 20 and coöperate with pins 24 projecting laterally from bars 25 which are supported upon the cross 20 rods 16. The levers 22 have slots 26 through which the pins 24 pass so as to permit a certain degree of movement of the levers 22 downwardly in the shifting of the seat. At the extreme ends of the levers 22 there are 25 pins 27 which coöperate with yokes 28 to secure to the upper side thereof rockers 29 carrying a cushion 30. The rockers 29 have inclined surfaces 31 on their lower sides to support the cushion 30 from the cross rods 30 35 16 and to give the cushion 30 its required angle. The outer plate 10 has an upper flange 32 and a lower flange 33 to inclose as far as possible the mechanism for shifting the car seat, while the inner plate 9 has at the sides 35 thereof right-angle extensions 33^a adjacent to further extensions 34 located parallel to the plate 9, adjacent to which there are located other right-angle extensions 35, while the plate 9 terminates with a flange 36 40 extending in a reverse direction and parallel to the inner plate 9. As seen in Fig. 3, the outer plate 10 seats against the extensions 34 and is riveted thereto by means of rivets 37. Furthermore, the location of these parts permits the insertion of an arm rest 38 in the 45 recess formed between the flanges 36 and the outer plate 10. The arm rest 38 may, if desired, be held at the right elevation by bolts 39 passing through the flanges 36, the arm rest 38, the outer plates 10, and the extensions 34. This arrangement provides an unusually strong construction for the casing of the car seat, in view of the great horizontal width of the offset extensions on the 50 ends of the inner plates 9, while, at the same time, the arm rest 38 is more securely held in position and, in fact, is held in such a manner that no weight which the arm rests will be subjected to can move the same out of 55 alinement.

While I have described my invention above in detail, I wish it to be understood that many changes may be made therein without departing from the spirit of my invention.

I claim:

1. A shiftable car seat having at one end thereof a pair of supporting levers, each of which has two alternately operating fixed pivots. 70
2. A shiftable car seat having at one end thereof a pair of supporting levers, each of which has two alternately operating fixed pivots, and guiding means limiting the movement of the levers. 75
3. A shiftable car seat having at one end thereof a pair of supporting levers, each of which has two alternately operating fixed pivots, and guiding means limiting the movement of the levers, comprising rods attached to the levers and slotted plates coöperating therewith. 80
4. A shiftable car seat having at one end thereof a pair of supporting levers, each of which has two alternately operating fixed pivots, and guiding means limiting the movement of the levers, comprising rods attached to the levers and slotted plates coöperating therewith, the slotted plates having pivot pins for the levers. 90
5. A shiftable car seat having at each end thereof a pair of supporting levers, each of which has two alternately operating fixed pivots, and guiding means limiting the movement of the levers, comprising rods attached to the corresponding levers at the two ends of the car seat, and slotted plates coöperating therewith. 95
6. A shiftable car seat having at each end thereof a pair of supporting levers, each of which has two alternately operating fixed pivots, and guiding means limiting the movement of the levers, comprising rods attached to the corresponding levers at the two ends of the car seat and slotted plates coöperating therewith, the slotted plates having pivot pins for the levers. 100
7. A shiftable car seat having at one end thereof a pair of supporting levers, each of which has two alternately operating fixed pivots, and a back shifted thereby. 110
8. A shiftable car seat having at one end thereof a pair of supporting levers, each of which has two alternately operating fixed pivots, guiding means limiting the movement of the levers, and a back shifted thereby. 115
9. A shiftable car seat having at one end thereof a pair of supporting levers, each of which has two alternately operating fixed pivots, guiding means limiting the movement of the levers, comprising rods attached to the levers and slotted plates coöperating therewith, and a back shifted thereby. 120
10. A shiftable car seat having at one end thereof a pair of supporting levers, each of which has two alternately operating fixed pivots, guiding means limiting the movement of the levers, comprising rods attached to the levers and slotted plates coöperating 125
11. A shiftable car seat having at one end thereof a pair of supporting levers, each of which has two alternately operating fixed pivots, guiding means limiting the movement of the levers, comprising rods attached to the levers and slotted plates coöperating 130

therewith, the slotted plates having pivot pins for the levers, and a back shifted thereby.

11. A shiftable car seat having at each end thereof a pair of supporting levers, each of which has two alternately operating fixed pivots, guiding means limiting the movement of the levers, comprising rods attached to the corresponding levers at the two ends of the car seat, and slotted plates coöperating therewith, and a back shifted thereby.

12. A shiftable car seat having at each end thereof a pair of supporting levers, each of which has two alternately operating fixed pivots, guiding means limiting the movement of the levers, comprising rods attached to the corresponding levers at the two ends of the car seat and slotted plates coöperating therewith, the slotted plates having pivot pins for the levers, and a back shifted thereby.

13. A shiftable car seat having at one end thereof a pair of supporting levers, each of which has two alternately operating fixed pivots and a foot rest and cushion shifted thereby.

14. A shiftable car seat having at one end thereof a pair of supporting levers, each of which has two alternately operating fixed pivots, guiding means limiting the movement of the levers, and a foot rest and cushion shifted thereby.

15. A shiftable car seat having at one end thereof a pair of supporting levers, each of which has two alternately operating fixed pivots, guiding means limiting the movement of the levers, comprising rods attached to the levers and slotted plates coöperating therewith, and a foot rest and cushion shifted thereby.

16. A shiftable car seat having at one end thereof a pair of supporting levers, each of which has two alternately operating fixed pivots, guiding means limiting the movement of the levers, comprising rods attached to the levers and slotted plates coöperating therewith, the slotted plates having pivot pins for the levers, and a foot rest and cushion shifted thereby.

17. A shiftable car seat having at each end thereof a pair of supporting levers, each of which has two alternately operating fixed

pivots, guiding means limiting the movement of the levers, comprising rods attached to the corresponding levers at the two ends 55 of the car seat, and slotted plates coöperating therewith, and a foot rest and cushion shifted thereby.

18. A shiftable car seat having at each end thereof a pair of supporting levers, each of which has two alternately operating fixed pivots, guiding means limiting the movement of the levers, comprising rods attached to the corresponding levers at the two ends of the car seat and slotted plates coöperating therewith, the slotted plates having pivot pins for the levers, and a foot rest and cushion shifted thereby.

19. A shiftable car seat having at an end thereof a supporting lever having two alternately operating fixed pivots and a central guide rod limiting the movement of the lever.

20. A shiftable car seat having at an end thereof a supporting lever having two alternately operating fixed pivots, a central guide rod limiting the movement of the lever, and a foot rest lever shifted thereby.

21. A shiftable car seat having at an end thereof a supporting lever having two alternately operating fixed pivots, a central guide rod limiting the movement of the lever, a carriage attached thereto, and a foot rest lever shifted thereby.

22. A shiftable car seat having at an end thereof a supporting lever having two alternately operating fixed pivots, a central guide rod limiting the movement of the lever, a foot rest lever shifted thereby, and a fixed pivot having slotted connection to the foot 90 rest lever.

23. A shiftable car seat having at an end thereof a supporting lever having two alternately operating fixed pivots, a central guide rod limiting the movement of the lever, a carriage attached thereto, a foot rest lever shifted thereby, and a fixed pivot having slotted connection to the foot rest lever.

In testimony that I claim the foregoing I have hereunto set my hand.

SHERIDAN A. WALKER.
